CLAIM

The ornamental design for an end-of-train LED beacon,
as shown and described.

DESCRIPTION

FIG. 1 is a front perspective view of an end-of-train LED beacon showing my new design;

FIG. 2 is a top plan view thereof, the bottom being a
mirror image;

FIG. 3 is a side elevational view thereof, the opposite
side being a mirror image;

FIG. 4 is a rear elevational view thereof;

FIG. 5 is front elevational view thereof on an enlarged
scale.

FIG. 1

FIG. 2

FIG. 3

FIG. 4

FIG. 5
